[57] CLAIM

The ornamental design for an antenna rotator control, as shown.

DESCRIPTION

FIG. 1 is a perspective view of one embodiment of an antenna rotor control constructed according to this invention;

FIG. 2 is a plan view of the antenna rotator control shown in FIG. 1;

FIG. 3 is a front elevational view of the antenna rotator control shown in FIG. 1;

FIG. 4 is a rear elevational view of the antenna rotator control shown in FIG. 1;

FIG. 5 is an elevational view of the left side of the antenna rotator control shown in FIG. 1.
